ELECTRIC MASSAGE MACHINE VIBRATOR

Filed Jan. 21, 1929

Inventor
Charles W. Kent.

C. W. Kent.
Atty.

UNITED STATES PATENT OFFICE

CHARLES W. KENT, OF PEORIA, ILLINOIS

ELECTRIC MASSAGE MACHINE VIBRATOR

Application filed January 21, 1929. Serial No. 333,767.

My invention relates more particularly to the vibrators used in the comparatively small electric massage machines which are primarily adapted to be held in the hand of the user, and are usually operated by one or more of the small types of dry batteries which are slipped into the handle portion of the machine and furnish the operating current, though my invention is not necessarily limited to this type of machine or to this use.

One object of my invention is the provision of an adjustable vibrator provided with a relatively heavy shield or guard whereby the delicate parts of the vibrator are protected from injury.

Another object of my invention is to construct and arrange the guard so that it forms a part of the electrical circuit from the battery to the primary coil, thus combining the functions of protection to the parts and establishing contact with the battery.

Other objects of my invention will appear and be described in the specification.

The novelty of my invention will be herein-after more fully set forth and specifically pointed out in the claim.

In the accompanying drawings, in which the parts are shown approximately twice full size:

Fig. 1 is a central sectional side elevation of the major portion of an electric massage machine showing my vibrator and associated parts in their proper arrangement and position.

Fig. 2 is an end view of the vibrator parts with the guard removed.

Fig. 3 is a view corresponding to Fig. 2 but with the guard in position.

Fig. 4 is a side view of Fig. 3.

The same numerals of reference are used to indicate identical parts in all the figures.

As showing one form of device embodying my invention, though without limiting myself to the precise details of construction and arrangement of parts, but availing myself of all changes and modifications which may be made within the scope of the appended claim, I have shown a device comprising a handle portion 5 which is usually a metallic tube which forms one of the terminals of both

the primary and secondary currents, this tube being usually provided at its upper end with a plug or cap 6, either of insulating material or insulated from the handle portion 5 and usually carrying a roller or other suitable terminal for the secondary current, the connection to which will be described later.

The plug 6 usually carries a rod or tube of insulating material 7, to the lower end of which the primary coil 8 is attached, the lower end of this coil carrying a disc 9, preferably of bakelite or other suitable insulating material, the disc 9 carrying the parts of the vibrator and its guard.

On the under side of the disc 9 the vibrator proper 10 is mounted as by screws 11, the vibrator being provided with an armature 12 and a contact 13. One terminal of the primary coil as shown at 14, passes through the disc 9 and is connected to the vibrator 10.

A second member 15 is secured to the disc 9 and is formed as shown in Fig. 2 and is bent over to bring its contact 16 into alignment with the contact 13, this member 15 being adapted to be adjusted by means of the screw 17, the screws 18 serving to hold it in position upon the disc. This member 15 has an extended portion 19 (Fig. 2) upon which one side of the guard rests when the guard is in position.

The guard 20 is shaped as shown in Figs. 3 and 4 so that its two ends rest upon the disc upon one side and the extension 19 upon the other, the guard being secured to the disc by screws 21, while its center portion is formed as a housing to protect the parts of the vibrator and as shown in Fig. 2, the central terminal 22 of the battery 23 rests against this guard and forms the electrical connection between the battery and the rest of the device.

In that form of device shown in Fig. 1, the secondary coil 24 is mounted within the handle to slide therein and is moved by a button 25 projecting through a slot in the handle.

A spring contact 26 is carried by the secondary coil and has one of its ends bent to form a contact with the handle 5, while its other end 27 forms a contact with a conductor 28 which extends from the disc 9 across the

coil 8 and part way up the tube 7, then passes through an opening in this tube to the inside thereof and is held in place by a plug 29. One terminal of the secondary coil is connected to the contact spring 26 and the second terminal 30 of the primary coil 8 is connected to the conductor 28.

A second conductor 31 extends from the disc 9 to a point about opposite the point to which the conductor 28 passes within the tube 7, where it also passes within this tube and is likewise held by the plug 29, this conductor extending up through the plug or cap 6 and is connected to the roller or other secondary terminal of the device. A spring contact 32 is carried by the secondary coil 24 and is connected to the other terminal of this coil and establishes a contact with the conductor 31.

I have described these parts of the device so that the electrical connections will appear complete which they do with the exception of the lower portion of the handle, which, as is usual in these devices carries a removable cap to afford means of placing the battery within the handle, this cap being usually provided with a spring which establishes electrical connection between the other terminal of the battery and the handle 5.

The primary electrical circuit is as follows. The handle 5 is in electrical contact with one terminal of the battery 23, which battery may consist of one or more cells, the other terminal of the battery 22 being in contact with the guard 20 which in turn is in contact with the member 15, the latter carrying the contact point 16 normally resting in contact with the contact 13 carried by the vibrator 10. The lead 14 extends from the vibrator 10 to one terminal of the primary coil, the other terminal 30 being connected to the conductor 28, upon which the spring contact 27 rides when the secondary coil is in the position shown in Fig. 1, this contact 27 being part of the spring 26 which is in contact with the handle 5 completes the primary electrical circuit. In the construction shown if the secondary coil is moved upward, the contact 27 moves past the exposed portion of the conductor 28 and opens the circuit.

During the flow of current, when the secondary coil is in a position where its contact 27 is upon the conductor 28, the coil 8 is energized and its pole pulls the armature 12 and the vibrator 10 upward thus opening the circuit between the contacts 13 and 16 which results in demagnetizing the pole whereupon the armature and vibrator move back into contact in the ordinary way.

Owing to the comparative smallness and delicacy of the parts and to the further fact that these parts have only a very small range of movement it is advisable that means for properly setting the position of the contacts 13 and 16 be provided and to this end the

screw 17 is employed, this screw acting to not only adjust the position of the member 15 and its contact 16 but to provide a movement limit for the downward movement of the member 15, or in other words to dampen its movement in one direction while at the same time permitting this member to vibrate at its outer end though not as freely as it would without the screw 17.

This portion of the device constitutes an adjustable vibrator and, by means of this adjustment the distance between the armature 12 and the pole of the coil 8 may be varied while at the same time the other construction is such, that while in operation, the parts are acting yieldingly, thereby producing a vibrator which stands up well in service and one which consists of very few simple parts which, when mounted as shown and protected by the member 20 are not subject to derangement in use even though the device may accidentally fall and strike in such way that the weight of the battery would come upon the guard 20.

It is to be noted that the operating parts of the vibrator are mounted on the disc 9 so that even if the guard 20 should be sprung or bent accidentally, no disturbance of the setting of the parts would occur, unless of course the guard were to collapse to an extent which should bring it in contact with the parts of the vibrator, which condition, owing to the substantial character of the guard 20 is extremely remote.

Having thus fully described my invention, I claim:

In a massage machine vibrator the combination of a handle portion, a primary coil mounted therein, an insulating disc adjacent one end of the coil, vibrator parts comprising a spring mounted vibrator carried by the disc, a spring mounted contact member carried by the disc and cooperating with the spring mounting for the vibrator, means for adjusting the contact member, a guard carried by the disc and substantially inclosing the vibrator parts and in electrical connection with one thereof, and a battery within the handle and in electrical contact with the guard.

CHARLES W. KENT.
